UNITED STATES PATENT OFFICE.

FRANKLIN LENZNER, OF CASS CITY, MICHIGAN.

MOTOR-FAN.

SPECIFICATION forming part of Letters Patent No. 616,712, dated December 27, 1898.

Application filed December 2, 1897. Serial No. 660,517. (No model.)

To all whom it may concern:

Be it known that I, FRANKLIN LENZNER, of Cass City, in the county of Tuscola and State of Michigan, have invented a new and Improved Motor-Fan, of which the following is a full, clear, and exact description.

This invention is a fan adapted to be placed in apartments, particularly over one's bed, so that persons beneath the fan may be kept cool without any more exertion than is required to wind the mechanical motor with which the invention is equipped.

This specification is the disclosure of one form of my invention, while the claims define the actual scope thereof.

Reference is to be had to the accompanying drawings, forming a part of this specification, in which similar characters of reference indicate corresponding parts in all the figures.

20 Figure 1 is a perspective view of the invention, showing it applied to a bedstead. Fig. 2 is a sectional view of the fan, showing the means for extending the blades thereof. Fig. 3 is a vertical section taken through said means.

25 Fig. 4 is a fragmentary elevation illustrating the fan, and Fig. 5 is a perspective view showing the wheel by which the fan-blades are extended and contracted.

My invention is shown as applied to a bedstead; but it is obvious that it may be supported and applied in other ways. The mechanical motor is mounted in a casing 11, which is suitably attached to the bed.

The fan is provided with two blades 39, which may have any desired construction and which are supported on arms, each formed of two runs of wire 37 and 38, joined at their outer ends by cross-bars 40, one of which is shown in full lines both in Figs. 1 and 2 and 40 one of which is shown by dotted lines in Fig. 2. The runs 37 and 38 on each fan-arm are braced at their inner ends by the respective bars 40^a, similar to the bars 40. The arms of the fan-blades pass through a flat open-end

45 casing 41, and the wires 38 being of serpentine or undulatory form mesh with oppositely extending lateral fingers 42, carried on a wheel 43, fixed upon a spindle 44, mounted in the casing 41. By these means the arms 50 of the fan-blades may be moved oppositely and simultaneously, so as to advance the blades 39 toward and from each other, and thereby regulate the sweep of the fan. The

casing 41 has the tube 24 rigidly attached thereto, so that the casing, and consequently 55 the fan, may be connected with the spindle 25. By means of a key applied to the spindle 44 the blades of the fan may be adjusted.

Having thus described my invention, I claim as new and desire to secure by Letters 60 Patent—

1. In a fan, the combination of a casing, a gear-wheel mounted therein, two fan-blades, and an arm secured to each fan-blade and passing through the casing and meshing with 65 the gear, so that the arms may be extended and contracted by the action of the gear.

2. In a fan, the combination of a casing, two fan-blades, two arms secured respectively to the blades, each arm having a serpentine 70 or undulatory portion, and a gear-wheel mounted in the casing and engaged at opposite points by said serpentine or undulatory portions, the gear-wheel having fingers projecting laterally from each side thereof to 75 engage with said serpentine or undulatory portions.

3. The combination of a casing, two fan-arms mounted to slide therein, a gear-wheel meshing with said arms to move the same, 80 and a fan-blade carried by each arm.

4. The combination of a casing, a gear-wheel mounted therein, the gear-wheel having two sets of lateral fingers extending in opposite directions, two fan-arms, each arm 85 having a serpentine portion, such portions being respectively engaged with the fingers of the gear-wheel, and fan-blades carried by the fan-arms.

5. The combination of a casing, two fan-arms mounted to slide therein, means for moving the fan-arms, such means being carried by the casing, and fan-blades respectively carried by the fan-arms.

6. The combination of a casing, a gear-wheel mounted therein, two fan-blades, and two arms respectively carrying the blades and slidably in the casing, each arm being composed of two runs of wire, one run of each arm being serpentine in form so as to mesh 95 with the gear-wheel and receive the movement thereof.

FRANKLIN LENZNER.
